UNITED STATES PATENT OFFICE.

OTTO THUM AND WILLIAM THUM, OF GRAND RAPIDS, MICHIGAN.

STICKY FLY-PAPER.

SPECIFICATION forming part of Reissued Letters Patent No. 11,276, dated October 11, 1892.

Original No. 414,606, dated November 5, 1889. Application for reissue filed August 7, 1891. Serial No. 402,049.

To all whom it may concern:

Be it known that we, OTTO THUM and WILLIAM THUM, citizens of the United States, residing at Grand Rapids, in the county of 5 Kent and State of Michigan, have invented certain new and useful Improvements in Sticky Fly-Catcher Sheets, of which the following is so full, clear, and exact a description as will enable others skilled in the art to 10 to which our invention appertains to make and use the same, reference being had to the accompanying drawings, in which—

Figure 1 is a plan view of a sheet of fly-paper having projections on its sticky portion. 15 Fig. 2 is a sectional view of Fig. 1. Fig. 3 is a sectional view showing the projections applied to the sticky surface, the confining-border, and the uncoated margin. Fig. 4 is a 20 sectional view of a portion of a sheet of fly-paper in which the projections are formed by indenting or corrugating the paper itself.

The objects of the invention are to prevent the sticky material from spreading or running over the clean margin and onto the back of 25 the sheets while the paper is kept in stock; also, to keep the sticky material evenly distributed on the sheet while it is kept in stock. This we accomplish by providing the surface with projections which will not be affected to 30 any appreciable extent by the ordinary variation of degrees of heat and cold and humidity incident to the surfaces during the process of handling at the manufactory, its shipment, and storage prior to its use as an 35 insect-catcher. We may use small seeds, ground emery, fragments of any kind of hard resin, or coarse sand, or any kind of hard material not soluble in sticky material or only slightly so will serve the purpose, the present 40 invention consisting, broadly, in providing the surface with projections of any kind to keep the ground-work of the sticky surface out of close contact with anything with which it may come in contact. Again, the hard substances 45 or projections will, by reason of capillary attraction, have a tendency to keep the sticky substance from flowing over the surface. In some instances the surface of the sheet may be provided with projections or depressions, or both; by corrugating, indenting, or other-

wise producing irregular configurations in the material of which the groundwork of the surface is composed. These projections may also be produced by sprinkling the surface with the granular material while in the condition of hard disintegrated particles; or, if a material which is soluble or fusible at a moderately-high degree of temperature and one which congeals at the ordinary degree of temperature—such as resin—be used it may be sprinkled or spread over the surface while hot and then be allowed to cool, care being taken to leave proper interstices between the deposits. After these projections shall have cooled and hardened the softer sticky 55 substance should be spread over the remaining surface to be covered with it within the margin which is to be left around the edges. This margin A is to be left free from sticky fly-catching material, and it is preferably 60 coated or partially coated with a resinous compound or other suitable material to form a retainer for the sticky fly-catching material. It is so placed and of such a nature that it surrounds the sticky material within the edge of 65 the sheets, and it slightly cements the clean borders of the facing leaves of the sheets together in a manner to retain the sticky material until the sheets are opened for use. 70 The projections B, when produced by 75 sprinkling, may be sprinkled over the surface either before the sticky substance C is applied to the surface or afterward; but we think it preferable to sprinkle the surface before the sticky substance C is applied, the projections being glued or otherwise secured to the sheet, as by that means the projections 80 will have a firm hold on the surface proper, and being thus immovably secured to the surface of the groundwork of the sheets they 85 will keep two adjacent surfaces well apart, even if the sticky material should become heated (or for any other reason) and have a tendency to flow beyond and without its proper 90 precincts. Aside from this, such projections as are within the precincts of the sticky material will thus be coated with the sticky fly-catching material. The points of contact of the projections as they are pressed against another surface will be so comparatively 95

small as to prevent them from adhering to any appreciably disadvantageous or injurious extent.

Instead of sprinkling the projections on before the sticky substance is applied they might be mixed with the sticky substance itself, and would then serve to keep the main portions of the surfaces of the groundwork apart and would still be covered by the sticky substance, 10 as shown at E, although we do not limit ourselves to having them so covered or coated.

For the purpose of shipping there are from twenty-five to fifty sheets of fly-paper packed in a box. A considerable pressure is borne 15 by the lower sheets; but if the proper-sized particles exist on the inner surface of the paper the pressure will fall entirely on them, and thus relieve the sticky material altogether, which then will not press out, as would otherwise be the case, but will only flow out by its 20 own tendency to spread, as any other semi-liquid would. This tendency alone will not spread the sticky material enough to do any special damage, as the capillary attraction of 25 the projections will largely prevent this. The small particles also lessen the spreading tendency not due to pressure. They keep the sheets apart the distance of their (the particles) diameter, so that the leaves of the sheet 30 could not come nearer together even if the sticky material lowered by spreading out.

After fly-papers are spread with sticky material the sheets often become wrinkled or wavy from various causes, such as absorbed 35 moisture slightly swelling the backs of the paper, or the paper may be wavy to start with, &c. In such cases the sticky material will collect in the folds, leaving the remaining surface nearly bare. On opening such a sheet 40 the sticky material will be found distributed unevenly. The small particles obviate this fault to a great degree, because a wrinkle formed in one leaf of the sheet will be held away from the other leaf by the small particles a sufficient distance to hold the proper 45 amount of sticky material. Therefore it will not be pressed to one side.

In the form shown in Fig. 3 the projections extend over the entire sheet, thus making a 50 sheet the surface of which is of an approximately-uniform height, which will keep the entire sheet straight and flat, and the sticky fly-catcher material will naturally remain where it belongs, and all portions of the sheet 55 being in the same general plane and quite a

distance apart when placed together it will have no considerable tendency to flow over the margin.

Instead of the granular projections described for keeping the sheets, which are arranged in pairs or folded with the sticky surfaces in contact, a certain distance apart we have shown in Fig. 4 the sheet as corrugated to form projections for the same purpose—namely, to keep the sheets apart and to retard the flow of the sticky material.

Having thus described our invention, what we claim is—

1. Sticky fly-paper having a coated portion and uncoated margin and projections extending from the surface, substantially as described.

2. Sticky fly-paper having a series of projections extending from its coated surface and uncoated margins, substantially as described.

3. Sticky fly-paper having a coated portion, a confining-border, and an uncoated margin, and projections extending from the surface of the paper, substantially as described.

4. Sticky fly-paper having a coated portion, a confining-border, an uncoated margin, and projections extending from the entire surface.

5. A sticky fly-paper having projections of granular material embedded thereon.

6. A sticky fly-paper having projections of granular material which are insoluble in the sticky material.

7. A sticky fly-paper provided with granular projections distributed over the sticky portion of the sheet, exceeding or as deep as the sticky material.

8. A sticky fly-paper provided with insoluble projections irregularly disposed over the sheet and surrounded by the sticky material.

9. A sticky fly-paper provided with irregular non-hygroscopic projections disposed over its surface.

10. A fly-catcher sheet provided with sticky fly-catching material and having insoluble projections, substantially as described, for preventing the flow of the fly-catcher material.

In testimony whereof we affix our signatures in presence of two witnesses.

OTTO THUM.
WILLIAM THUM.
